United States Patent Office

Des. 194,178
Patented Dec. 4, 1962

194,178

BATHTUB

William H. Armstrong, Birmingham, Mich., assignor to Borg-Warner Corporation, Chicago, Ill., a corporation of Illinois

Filed Feb. 19, 1960, Ser. No. 59,448

Term of patent 14 years

(Cl. D4—4)

Fig. 1

Fig. 2

Fig. 5

Fig. 4

FIGURE 1 is a perspective view of a bathtub embodying my new design.

FIG. 2 is a side elevation view thereof;

FIG. 3 is an enlarged fragmentary top plan view thereof taken along the line 3—3 of FIG. 2;

FIG. 4 is an enlarged vertical cross-sectional view taken along the line 4—4 of FIG. 2; and

FIG. 5 is an enlarged vertical cross-sectional view thereof taken along the line 5—5 of FIG. 3 and showing the outline of the portions included therein.

I claim:

The ornamental design for a bathtub, substantially as shown.
